VACUUM CLEANER

Joseph R. Mango, Midlothian, Ill., and Louis J. De La Marter, Lexington, and Frederick W. Perl, Mansfield, Ohio, assignors to Westinghouse Electric Corporation, East Pittsburgh, Pa., a corporation of Pennsylvania

Filed Oct. 4, 1963, Ser. No. 76,867

Term of patent 14 years

(Cl. D9—2)

FIG. 1 is a side elevational view of a vacuum cleaner embodying our invention;

FIG. 2 is a front elevational view thereof, taken from the left of FIG. 1; and

FIG. 3 is a rear elevational view thereof, taken from the right of FIG. 1.

The side not shown in FIG. 1 is similar in appearance to the side shown therein.

The electric cord is shown broken away in FIG. 2 for convenience of illustration.

It is to be understood that the crisscross pattern representative of cloth fabric partially shown in FIGS. 1, 2

and 3, covers the entire surface of the area indicated.

The dominant features of our design reside in the parts shown in full lines.

What we claim is:

The ornamental design for a vacuum cleaner, substantially as shown and described.
